DRAWER SLIDE

Carl J. Dargene, Rockford, Ill., assignor, by mesne assignments, to Amerock Corporation, Rockford, Ill., a corporation of Connecticut

Filed Oct. 9, 1963, Ser. No. 314,925
14 Claims. (Cl. 312—343)

This invention relates to a drawer slide of the type which includes supporting means such as an elongated track or channel mounted in a cabinet and receiving a roller carried by the drawer to guide the drawer as it slides in and out.

The principal object of the invention is to provide a new and improved drawer slide which, as compared to prior slides, requires fewer fastening elements and fewer steps to mount it in a cabinet but which is held accurately and securely in place once it is mounted in position.

A more detailed object is to construct the slide in a novel manner so that it may simply be snapped into place on a cross rail in the front of the cabinet and held on the rail without the use of fastening elements.

Other objects and advantages of the invention will become apparent from the following detailed description taken in connection with the accompanying drawings, in which

FIGURE 1 is a fragmentary perspective view of a cabinet in which the drawers are guided by a slide constructed according to the present invention.

FIG. 2 is an enlarged fragmentary sectional view taken along the line 2—2 in FIG. 1.

FIG. 3 is an enlarged sectional view taken along the line 3—3 in FIG. 2.

FIG. 4 is a fragmentary perspective view of the slide.

FIG. 5 is a fragmentary side view of the slide showing the end as it is prepared to be seated on the rail of the cabinet.

FIG. 6 is a view similar to FIG. 5 but with the parts in the mounted position.

FIG. 7 is a fragmentary top view of the slide.

FIG. 8 is an exploded fragmentary perspective view of the end portion of the slide.

FIG. 9 is a view of the slide.

FIG. 10 is a fragmentary perspective view of the slide.

FIG. 11 is an end view of a modified form of the invention.

FIG. 12 is a view similar to FIG. 6 but shows a further modification of the invention.

FIG. 13 is an exploded fragmentary perspective view of the form of slide shown in FIG. 12.

FIG. 14 is a view similar to FIG. 6 but shows still another embodiment of the invention.

FIG. 15 is a fragmentary side view illustrating the manner of mounting the form of slide shown in FIG. 14.

FIG. 16 is a fragmentary plan view of a modified form in which edges of the drawer are supported by rollers.

FIG. 17 is an enlarged fragmentary sectional view taken along the line 17—17 in FIG. 16.

FIG. 18 is a fragmentary plan view showing one of the rollers mounted in place.

FIG. 19 is a perspective view of a roller.

As shown in the drawings for purposes of illustration, the invention is embodied in a slide 20 (FIG. 2) for guiding the movement of the drawers 21 of a cabinet 22. The latter includes spaced front and back walls 23 and 24, sides 25 and a top 26 with the drawers 21 being inserted through rectangular openings 27 in the front wall to slide on cross rails 28 which form a part of the front wall. To support the drawer and to guide it as it is slid in and out, the slide includes anti-friction means which, in the preferred form, supports the rear of the drawer and includes

2

a roller 29 (FIG. 2) journaled on a bracket 30 which is fastened to the rear of the drawer with the roller riding in an elongated track 31 which forms the principal component of the slide 20.

The track 31 is channel-shaped in cross section, opening to one side, and substantially spans the front and back walls 23 and 24. One end of the channel is fastened to the back wall by means of a bracket 32 which, herein, receives the channel and is mounted on the wall by nails or the like and the other end of the channel is supported by a rail 28.

The present invention contemplates the provision of a drawer slide with a novel means for securing it to the rail 28 without the use of fastening elements such as nails, screws and the like. With the invention, the slide is merely snapped into place relative to the rail and, when in place, it is securely held and accurately positioned. To these ends, this means comprises an inverted U-shaped end piece 33 carried by the slide so that the outer leg 34 of the piece projects down into a slot or kerf 35 in the upper side 36 of the rail 28 and the inner leg 37 lies against the inner face 38 of the rail, the cross piece 39 of the U resting on the upper side of the rail. Preferably, a horizontal flange 40 projects forwardly from the lower end of the inner leg 37 to be received in a kerf 41 in the face 38 of the rail so that the end piece 33 may be snapped into place with the leg 34 and the flange 40 projecting into the kerfs 35 and 41 to position the slide and prevent its removal.

In the preferred form of the invention illustrated in FIGS. 1 through 10, the piece 33 is used to mount the channel 31 and is formed separately from the channel but is pivotally connected to the outer end of the latter so that the inner end of the channel may be inserted in the bracket 32 before the outer end is positioned relative to the rail 28. Thus, the outer end portion 42 of the channel is flattened and overlaps a flat, rearwardly projecting bar or flange 43 on the piece 33. A rivet 44 projects through holes 45 and 46 (FIG. 8) in the end portion 42 and the flange 43 to constitute the pivot connecting the piece 33 and the channel 31.

With the foregoing arrangement, the slide 20 is mounted in the cabinet 22 by first inserting the inner end of the channel 31 in the bracket 32. At this time, the channel is in a position in which it is tilted upwardly and the piece 33 is turned down relative to the channel as shown in FIG. 2. With the parts thus positioned, the end of the outer leg 34 is located over the kerf 35 and the flange 40 is bearing against the inner face 38 of the rail 28 above the kerf 41. Then, the mounting is completed by pushing down on the slide adjacent the pivot 44. This forces the leg 34 into the kerf 35 and straightens the piece 33 relative to the channel 31 so that the flange 40 slides down along the face 38 of the rail 28 and snaps into the kerf 41 at which time the leg 37 lies against the face 38. The legs 34 and 37 and the flange 40 yield slightly during this final mounting step to permit the flange to slide toward the kerf 41 and snap into position. If desired, the leg 34 may be bent outwardly a small amount and the end of the flange 40 flared downwardly as illustrated at 47 in FIG. 5 to help guide these parts into their respective kerfs. When the leg 37 is against the rail 28, the pivot 44 cannot move further downwardly and the piece 33 and channel 31 are rigid relative to each other under the weight of the drawer 21 as transmitted through the roller 29. Preferably, the leg 37 is received in a recess 38a (FIG. 5) which is cut in the face 38 and which is approximately the same width as the leg to prevent the piece 33 from moving laterally along the rail 28.

Preferably, means is provided to latch the piece 33 against movement relative to the channel 31 after the

slide 20 is in its mounted position thereby to prevent the slide from being lifted out of the cabinet and afford a relatively permanent mounting of the slide. This means comprises a latch or detent 48 which is connected to the piece 33 and engages a surface 49 on the channel 31 to prevent the piece from turning clockwise relative to the channel after the parts reach their final mounted position.

In the form shown in FIG. 1 through 10, the detent 48 is an ear struck out laterally from the flange 43 adjacent the lower edge thereof and in the front half of the flange. In back of the ear 48, the flange is cut away as indicated at 50 (FIG. 8) to form a rearwardly facing edge 51 offset from the plane of the flange. The edge 51 is spaced in front of the pivot 44 a distance equal to the distance between the pivot and the forward end of the channel 31, it being this end of the channel which constitutes the surface 49 which is engaged by the detent or ear 48. Thus, when the piece 33 is turned relative to the channel as shown in FIGS. 2 and 6, the flange 43 and the end portion 42 of the channel yield slightly to permit the ear to pass alongside this end portion as the slide 20 is mounted. As the piece 33 becomes seated on the rail 28 with the leg 34 and flange 49 projected into the kerfs 35 and 41, the ear 48 passes beyond the end of the channel and snaps over in front of the channel end portion 42 so that the edge 51 of the ear engages the end 49 of the channel. Such engagement prevents the end piece 33 from turning back and locks the entire slide 20 in the mounted position.

If desired, a lock washer 52 may be used under the head of the rivet 44 as shown in FIG. 11. In such a case, the lock washer may be especially adapted to constitute the latch 48 as shown in FIGS. 12 and 13 in which the parts corresponding to those of the preferred embodiment are indicated by the same but primed reference characters. For this purpose, the flange 43' is struck out of the leg 37' of the end piece 33' so that the flange is centrally disposed relative to the end piece and the holes 46' and 45' in the flange and the end portion 42' of the channel 31' are adjacent the upper and forward edges of these parts. A square hole 53 is cut in the end portion 42' and a square notch 54 is cut in the edge of the flange 43' to match the hole 53 when the end piece 33' is fully seated on the rail 28'. Integral with the washer 52' is a spring finger 55 which projects into the notch 54 and is biased toward the channel end portion 42'. When the notch and the hole 53 are alined, the finger snaps into the hole and holds the flange 43' and the end portion 42' against relative turning.

In the embodiment illustrated in FIGS. 14 and 15, the U-shaped end piece 33" is formed integrally with the channel 31" on the outer end thereof. The configuration and function of the legs 34" and 37", the crosspiece 39" and the flange 40", however, are the same as in the preferred form of the invention. The principal difference resides in the fact that the mounting steps are reversed. Instead of fastening the bracket 32" to the back wall 24" of the cabinet, the bracket is simply slipped over the inner end of the channel 31". The latter then is tilted as shown in FIG. 15, to prepare the leg 34" and flange 40" for entry into the kerfs 35" and 41" in the rail 28". Then the channel is swung counterclockwise to seat the end piece 33" on the rail and to bring the channel to the horizontal position shown in broken lines in FIG. 15, the back wall 24" bowing slightly to permit such swinging. Finally, the bracket 32" is nailed, stapled or otherwise fastened to the back wall.

The invention may also be utilized in connection with anti-friction means for supporting and guiding the edges of the drawer 21 as illustrated in FIGS. 16 through 19. In this case, the anti-friction means comprises two rollers 56 mounted on the cross rail 28 of the cabinet with one mounted at each side of the drawer to support the respective side panels 57 of the drawer. The rollers may, as shown, be used in conjunction with a channel 31 and roller

29 which are identical in construction to that shown in FIGS. 1 through 10.

Each roller 56 is carried by a piece 58 which, like the piece 33, is mounted on the cross rail 28 by utilizing the kerfs 35 and 41 and without fastening elements. Thus, each roller is supported by a U-shaped piece 58 which is formed with one leg 59 projecting down into the kerf 35 and the other leg 60 lying against the inside of the cross rail in a recess 61 (FIG. 18), the crosspiece 62 lying on the top of the rail. Since the piece 58 is the only means of support for the roller 56, the leg 59 is bent inwardly a small amount so that the cross rail 28 is gripped firmly between the two legs 59 and 60. The flange 63 which projects into the kerf 41 extends across only the central portion of the leg 60 and is in the form of an ear struck out from the body of the piece 58.

To support the roller 56, arms 64 integral with the piece 58 project rearwardly from opposite side edges of the leg 60 and the roller is disposed between these arms and journaled on the latter by means of a pin or axle 65. The roller may be molded from a suitable plastic material and is formed with a radial flange 66 which is adapted to engage the outside of the corresponding drawer panel 57 to hold the drawer against lateral shifting as it is slid in and out.

It will be observed that, with a slide 20 constructed according to the present invention, the only fastening elements required to mount the slide in a cabinet 22 are those used to fasten the bracket 32 to the back wall 24. Beyond that, the slide merely is snapped into place and, when mounted, it is held securely in the cabinet. The only special preparation required is the cutting of the kerfs 35 and 41 and this may be done by high speed production methods during the manufacture of the cabinet.

I claim as my invention:

1. A guide unit for controlling movement of a drawer along a fixed line of travel between open and closed positions relative to a drawer containing area defined by a horizontal front support and a track support in rearwardly spaced opposed relation to said front support, a track member having a rear end portion with which said track support cooperates to provide a horizontal axis about which said track member has downward rocking movement to effect movement of the forward end of said track member into a downward position conforming to an operative position of said track member wherein said track member extends along a fixed line in rearwardly projecting relation to said front support, said track member being sufficiently shorter than the distance between said front support and said track support measured lengthwise of said line as to permit the forward end of said track member to clear said front support while undergoing movement into said downward position, a track extension member pivotally connected to said forward end of the track member for swinging movement relative to said track member between a forwardly extended position and a rearwardly retracted position, said extension member engaging said front support and swinging relative to said track member from said rearwardly retracted position to said forwardly extended position as said track member is undergoing movement into said downward position, and said extension member having engagement with said front support to limit vertical movement of said track member relative to said front support while said track member is in said downward position and said extension member is in said forwardly extended position.

2. A guide unit according to claim 1, wherein said track member and said extension member have interengaging means effective to lock said extension member against movement to a retracted position from an extended position.

3. A guide unit according to claim 1, wherein said extension member has engagement with said front support to limit vertical movement of said track member relative to said front support via a projecting pair of for-

wardly projecting claw members spaced apart circumferentially of the arc of pivotal movement of said extension member relative to said track member.

4. A guide adapted to be mounted on horizontally spaced frame members of a cabinet and comprising a bracket adapted to be mounted on the inner side of one of said frame members, an elongated channel having one end received in said bracket and projecting horizontally toward the other of said frame members, a bar having one end pivotally connected to the other end of said channel to turn relative to the channel about an axis extending transversely of the channel, said bar having a U-shaped part rigidly connected to the other end of said bar and including inner and outer legs projecting downwardly and disposed in planes paralleling said axis, said inner leg bearing against the inner side of the other of said frame members and said outer leg projecting down into an upwardly opening slot formed in said other frame member, and a flange projecting forwardly from said inner leg and into a second slot formed in said inner side.

5. A guide adapted to be mounted on horizontally spaced frame members of a cabinet and comprising a bracket adapted to be mounted on the inner side of one of said frame members, an elongated channel having one end received in said bracket and projecting horizontally toward the other of said frame members, and a bar having one end pivotally connected to the other end of said channel to turn relative to the channel about an axis extending transversely of the channel, said bar having a U-shaped part rigidly connected to the other end of said bar and including inner and outer legs projecting downwardly and disposed in planes paralleling said axis, said inner leg bearing against the inner side of the other of said frame members and said outer leg projecting down into an upwardly opening slot formed in said other frame member.

6. A guide adapted to be mounted on spaced frame members of a cabinet to receive a roller carried by a drawer, said guide comprising an elongated channel extending horizontally between and substantially spanning said frame members, means secured to one of said frame members and removably receiving one end of said channel, an inverted U-shaped part overlapping the other end of said channel with the inner leg of said part bearing against the inner side of the other of said frame members and the outer leg projecting downwardly into an upwardly opening slot formed in said other frame member, and a pivot connecting the overlapped portions of said channel and said part whereby the latter may turn relative to the channel as said outer leg is projected into said slot.

7. A guide adapted to be mounted on horizontally spaced frame members of a cabinet and comprising a bracket adapted to be mounted on the inner side of one of said frame members, an elongated channel having one end received in said bracket and projecting horizontally toward the other of said frame members, a bar having one end pivotally connected to the other end of said channel to turn relative to the channel about an axis extending transversely of the channel, said bar having a U-shaped part rigidly connected to the other end of said bar and including inner and outer legs projecting downwardly and disposed in planes paralleling said axis, said inner leg bearing against the inner side of the other of said frame members and said outer leg projecting down into an upwardly opening slot formed in said other frame member, and a latch acting between said channel and said bar and operable to prevent upward movement of the pivotal connection between the two.

8. A guide adapted to be mounted on horizontally spaced frame members of a cabinet and comprising a bracket adapted to be mounted on the inner side of one of said frame members, an elongated channel having one end received in said bracket and projecting horizontally toward the other of said frame members, a bar having one

end pivotally connected to the other end of said channel to turn relative to the channel about an axis extending transversely of the channel, said bar having a U-shaped part rigidly connected to the other end of said bar and including inner and outer legs projecting downwardly and disposed in planes paralleling said axis, said inner leg bearing against the inner side of the other of said frame members and said outer leg projecting down into an upwardly opening slot formed in said other frame member, a flange projecting forwardly from the lower end of said inner leg into a second slot formed in said inner side, and a latch acting between said channel and said bar and operable to prevent upward movement of the pivotal connection between the two.

9. A guide adapted to be mounted on horizontally spaced frame members of a cabinet and comprising a bracket adapted to be mounted on the inner side of one of said frame members, an elongated channel having one end received in said bracket and projecting horizontally toward the other of said frame members, a bar having one end pivotally connected to the other end of said channel to turn relative to the channel about an axis extending transversely of the channel, said bar having a U-shaped part rigidly connected to the other end of said bar and including inner and outer legs projecting downwardly and disposed in planes paralleling said axis, said inner leg bearing against the inner side of the other of said frame members and said outer leg projecting down into an upwardly opening slot formed in said other frame member, and surfaces formed on said channel and said bar to oppose and abut each other when said inner leg bears against said inner side and prevent relative turning of the bar and the channel.

10. A guide adapted to be mounted on horizontally spaced frame members of a cabinet and comprising a bracket adapted to be mounted on the inner side of one of said frame members, an elongated channel having one end pivotally connected to the other end of said channel toward the other of said frame members, a bar having one end pivotally connected to the other end of said channel to turn relative to the channel about an axis extending transversely of the channel, said bar having a U-shaped part rigidly connected to the other end of said bar and including inner and outer legs projecting downwardly and disposed in planes paralleling said axis, said inner leg bearing against the inner side of the other of said frame members and said outer leg projecting down into an upwardly opening slot formed in said other frame member, surfaces formed respectively on said channel and said bar to be aligned when said inner leg bears against said inner side, and a spring finger carried by said channel and operable when said surfaces are aligned to snap in behind the surfaces and prevent relative turning of the bar and the channel.

11. In a cabinet having a drawer opening, the combination of, an elongated horizontal frame member extending along the bottom of said opening and having a first slot extending longitudinally thereof and formed in the upper side of said frame member, an inverted U-shaped part having a first leg projecting into said slot and a second leg lying against the inner side of said frame member and connected to said first leg by a cross piece, said frame member having a second longitudinal slot formed in said inner side, a flange rigid with said second leg and projecting into said second slot, the length of said cross piece being substantially equal to the distance from the inner side of said frame member to the adjacent side of said first slot and said flange being spaced from said cross piece a distance substantially equal to the spacing of the upper side of the frame member from the adjacent edge of said second slot, said U-shaped part being of resilient material to yield as said first leg and said flange are inserted in said slots and thereafter to grip said slot sides, and supporting means carried by said part and adapted to support and guide a drawer for sliding in said opening.

12. The combination as defined in claim 11 in which said supporting means is an elongated channel pivotally connected to said U-shaped part.

13. The combination as defined in claim 11 in which said supporting means is an elongated channel rigid with said U-shaped part.

14. The combination as defined in claim 11 in which said supporting means is a roller journaled on said U-shaped part.
